PUMPING SYSTEM

Edward J. Grace, Jr., Swarthmore, Pa., assignor
to Sun Oil Company, Philadelphia, Pa., a corporation of New Jersey

Application December 20, 1949, Serial No. 133,984

2 Claims. (Cl. 103—228)

1

The invention relates to pumping systems and particularly to the combination and arrangement of parts for lifting or transferring liquid containing solid particles from a sump or vessel to a pressured line or vessel.

The object of this invention is to provide means for pumping liquids containing debris from collecting areas which are common in manufacturing installations such as refineries and chemical plants where construction and alterations as well as cleaning operations are constantly in progress.

Manufacturing processes in which a slurry containing lumpy material is used will find the disclosed device an excellent means for transferring this slurry to pressure vessels as a step in the process. The usual suction line operated by a piston type pump and including check valves is objectionable as it clogs with pieces of weed, cinders, stones and miscellaneous solid materials present under such conditions. These objects in the liquid pumped through the system prevent the check valves from operating and cause rapid wear and constant replacement of bearings and shafts.

A transfer problem of this nature requires that the collecting pool, sump or other vessel be emptied by lifting the liquid to a pressure line or vessel. The pumping system of this invention includes the means for passing the contents of the collecting areas to such a pressure disposal pipe or vessel and includes a reciprocating piston or diaphragm pumping means for lifting the liquid and non-clogging check valves to keep the liquid moving against the pressure of the disposal locus. In the drawing, a schematic arrangement of the elements of the system is shown in elevation.

The numeral 10 indicates a collecting pool which contains liquid 11 and pieces of wood, stones and other debris, generally indicated at 12, as a typical example. A conduit 13 connects the pumping system with the liquid 11 and through the elements of the system to a pressure disposal line 14. A diaphragm or reciprocating piston pumping means 15 of commercial type is coupled to the conduit 13 at point 16 and furnishes the suction by which liquid 11 is lifted.

Between the pumping means 15 and the liquid source 11, a sealed chamber 17 containing a quantity of mercury 18, thereby forming a mercury check valve, is mounted. Considering the sections of the conduit 13 which connect the mercury check valve 17 as the induction section 13a and the eduction section 13b, it will be noted that the section 13a rises above the chamber 17 and enters it to sufficient depth to penetrate the mer-

cury body 18. The height to which the induction section 13a rises above the chamber depends upon the force which the pumping means exerts and must be sufficient to retain the mercury 18 in the chamber 17. The eduction section 13b connects the mercury check valve to the pump 15, leading directly from the top of the sealed chamber of the valve 17 without penetrating the mercury. The conduit is then extended to a mercury check valve 19 which is similar in construction in all respects to valve 17.

Considering the mercury check valve 19 which, like the valve 17, is a sealed chamber with a quantity of mercury 20 therein, an induction section 15 13c of the conduit line 13 enters the top of the chamber and penetrates the mercury surface, as explained above, for valve 17. As this valve is placed to protect the pumping system from the back pressure of the disposal line 14, the length of 20 the vertical leg 13c must be of sufficient height to prevent the mercury 20 from being forced out of the chamber 19 and up into the system against the flow of liquid and in response to the reciprocating suction action of the pump 15. An eduction section 13d connects the valve 19 to the line 14, as shown, and carries the effluent into that line for disposal.

An example of the operation of this system is given to clarify the application of the device in a 30 particular problem and indicate the method for determining the dimensions of the induction sections 13a and 13c under actual conditions. Referring to the drawing, numeral 21 represents a platform or elevated surface, in general, above a liquid body carrying silt, sand, pieces of mud, etc., as indicated at 10. The pump unit 15 is placed on the platform approximately twenty feet above the liquid to be lifted. It is required that the 40 delivery be one gallon per minute at a discharge pressure of 45 pounds absolute pressure with a speed of 30 strokes per minute. The diameter of the conduit 13c delivering to the discharge line 14, is taken as .6 inch. The height of the seal legs 13a and 13c are dictated by the absolute discharge pressure. The displacement of the pumping chamber in pump 15 must be greater than the volume required for the suction and discharge seals by a volume equal to the required pumping rate per stroke. As 2 inches of mercury equals 45 one pound pressure with an absolute pressure of lbs. assumed, the seal legs 13a and 13c must be 50 90 inches in height. From this dimension the mercury seal valves in which a two inch displacement of mercury is allowed, can readily be determined as 4 inches in diameter with a volume of

mercury approximately 50 cubic inches. The final step of determining the pump stroke displacement to properly operate this volume of mercury and cause the necessary lift and operation of the device gives a stroke volume of approximately 61 cubic inches.

The above example includes the complete analysis of the problem for determining the apparatus for the disclosed pumping system. This has been included in order to clearly describe the design of the induction and eduction conduits of the mercury check valves. It will be apparent to those versed in the art that the invention is applicable to any problem of pumping, in general, and may include gaseous as well as liquid fluids containing foreign and bulky material.

I claim:

1. In a pumping system the combination comprising a pump; a flow line cooperating with said pump; a flow check means upstream and above said pump in elevation consisting of a sealed chamber, a quantity of mercury therein, induction and eduction sections of said flow line connected to said chamber, the induction section vertically arranged to enter the mercury in said chamber and extending upwardly therefrom a distance sufficient to restrain the mercury to the locus of the sealed chamber; similar flow check means including a second sealed mercury-containing chamber downstream of said pump placed below the level of the pump a distance

sufficient to prevent the withdrawal of the mercury from said second chamber by the pumping action, the induction section of the second flow means arranged to enter the mercury in said second chamber and the eduction section thereof connected to said second chamber to conduct the effluent therefrom.

2. A system for lifting fluid from a source to a disposal point comprising a conduit having one end in communication with said source and the other end emptying into a disposal point above the level of the source, reciprocating pumping means positioned to operably engage said conduit between the source and the disposal point dividing it into an inlet and outlet section respectively, a mercury seal in the inlet section above the pumping means in elevation, a like seal in the outlet section below said pumping means in elevation, the conduit delivering the source material to the mercury seals having the end thereof immersed in the mercury and being vertically extended above said seals a sufficient distance to restrain the mercury to the seals during the pumping operation.
